CLOTHESPIN

John F. Donahue, Brooklyn, N. Y.

Application February 15, 1951, Serial No. 211,103

1 Claim. (Cl. 24—84)

1

This invention relates to a clothes pin which can be permanently suspended from the clothes line.

It is an object of the present invention to provide a clothes pin which can be connected on the clothes line and which is so constructed that it is made readily available to the user with the least possible effort, and when released and suspended from the line, the clothes pin overlaps and unites with adjacent pins to consume little space upon the line.

It is another object of the invention to provide a clothes pin adapted to be permanently connected to the line, the pin being double ended and can be swung to either one direction or to the other direction for its connection with the clothes on the line.

It is another object of the invention to provide in a clothes pin a clip member for the suspension of the clothes pin on the wire which can be sprung to permit the easy placing of the clip over the wire or the removal of the clip and clothes pin therefrom and also to provide a clip which will align the clothes pins upon the clothes line when not in use and when suspended thereupon.

Other objects of the invention are to provide a clothes pin adapted to be permanently connected to a clothes line, which is of simple construction, is inexpensive to manufacture, has a minimum number of parts, is easy to manipulate, durable, consumes little space upon the line, and is efficient to use.

For other objects and for a better understanding of the invention, reference may be had to the following detailed description taken in connection with the accompanying drawing in which

Fig. 1 is a perspective view of the clothes pin embodying the features of the present invention and constructed according to one form thereof.

Fig. 2 is a vertical sectional view taken on line 2—2 of Fig. 1.

Fig. 3 is a perspective view of the clothes pin extended over clothes upon the line and as applied thereto.

Fig. 4 is a vertical sectional view taken on line 4—4 of Fig. 3.

Fig. 5 is a perspective view of an assembly of several of the clothes pins upon the line.

Fig. 6 is a side elevational view of a modified form of the invention providing a double ended clothes pin.

Fig. 7 is a transverse sectional view taken on line 7—7 of Fig. 6.

Fig. 8 is a vertical sectional view taken on line 8—8 of Fig. 6.

2

Fig. 9 is a side elevational view of one of the elements of the double ended clothes pin shown in Fig. 6.

Fig. 10 is a side elevational view of the clothes pin in use on the line with one of the ends of the same extended over the clothing and line and with a dotted line illustration showing the application of the clothes pin from the opposite direction.

Fig. 11 is an assembly of two clothes pins upon the line and an edge elevational view thereof.

Referring now particularly to Figs. 1 to 5, 14 represents the clothes pin body which in section, as viewed in Fig. 4, has the general shape of a clothes pin with a clothes pin opening for receiving the line and garment, as indicated at 15. On the upper end of the clothes pin portion 14 is a handle formation 16 which is roughened at 17 to provide a good finger grip. Grooves 18 and 19 are provided on opposite side faces of the body to further facilitate the grip of the clothes pin.

The inner faces of the body 14 are tapered, as indicated at 21, to permit the easy sliding of the clothes pin over the line. The bottom edge of the body is rounded, as indicated at 22, to further facilitate the movement of the clothes pin over the line. The clamping action of the body is effected upon the clothes 23 and line 24 by the left side of the clothes pin body as viewed in Figs. 1, 2 and 3.

Upon the entering side of the body 14, the upper corner of the handle portion is recessed at the opposite sides thereof to provide respectively shoulders 25 and 26, against which suspending line 27 can abut to limit to some extent the relative pivotal movement of the loop element 27 and the body 14. The loop extends through an opening 28 in the handle portion 16 and is elongated in order to permit adequate vertical movement of the clothes pin body 14 when being manipulated to a position above the line for securing thereupon. The loop element 27 is severed on one side thereof, as indicated at 29, to permit the placing of the clothes pins upon the line 24.

It will now be apparent that the operation of placing the clothes pin upon the line and upon the clothes 23 can be done in the manner illustrated in Fig. 3 by a mere swinging upwardly of the clothes pin body 14 and the loop over the clothes pin to a position as shown in Fig. 3 and inclined to present the flared open side of the clothes pin body so that it can be dropped downwardly over the clothes 23 and the line 24 and thereafter readily straightened into its final gripping relationship therewith. The loop element

27 is of substantially the same length as the body element 14 so as to provide for adequate vertical adjustment of the body element upon the line.

In Fig. 5 there is shown an assembly of the clothes pins upon the line 24, and it will be seen that by a simple angling of the loop upon the line that the bodies 14 can be aligned in a side by side relationship so that they consume little longitudinal space along the line.

Referring now particularly to Figs. 6 to 11, there is shown a double end construction. Two body parts 31 and 32 are shaped to fit one another along line 33, Fig. 8. These parts respectively have openings 34 and 35 therein which register with one another and through which a loop retaining element 36 extends. This element has its ends 37 and 38 overlapping one another and the end 37 flared so as to receive the clothes line upon the insertion of the same into the loop element 36. The upper end of the loop element is twisted, as shown at 39, to lie in a different plane from the main portions of the loop element and which has opening 40 therein through which the line 24 can extend.

Each of the body elements 31 and 32 are of oval shape and have respectively indentations 42 and 43 in the opposite ends, which cooperate to provide an opening 44 for receiving the clothes line 24 and the clothes 23.

As illustrated in Fig. 10, the clothes pin, when lifted upwardly and twisted, can have its twisted portion 39 drop below the clothes line and the body elements aligned to be extended over the clothes line 24 either in the full line position, as shown in Fig. 10, or in the dotted line position with the opposite end extended over the line 24. The twisted upper end 39 of the element 36 will hold the clothes pin assemblies suspended from the line in the manner as shown in Fig. 11, and against angular displacement relative thereto

while being suspended and for free sliding movement over the line.

While various changes may be made in the detail construction, it shall be understood that such changes shall be within the spirit and scope of the present invention as defined by the appended claim.

What is claimed is:

A clothes pin assembly adapted to be suspended from a clothes line comprising a clothes pin body element having two relatively wide flat resilient sides and a clothes line opening therebetween and a block like handle portion extending across the top thereof, said handle portion having roughened sides, an elongated loop element pivotally connected to the top of the body, and adapted to pivot downwardly for alignment of its opening with the side of the opening in the clothes pin body and the handle portion of the clothes pin body being formed at one end thereof to provide shoulders at the opposite sides of the body against which said loop element can abut to limit the angular displacement of the loop element and the body element.

JOHN F. DONAHUE.
